UNITED STATES PATENT OFFICE.

EDWIN A. ROBERTSON, OF LAKE WAWASEE, INDIANA, ASSIGNOR, BY MESNE ASSIGNMENTS, TO THE WAYNE HOME EQUIPMENT COMPANY, OF FORT WAYNE, INDIANA, A CORPORATION OF MARYLAND.

SWITCH MECHANISM.

Application filed September 10, 1927. Serial No. 218,784.

My invention relates to switch mechanisms.

The principal object of my invention is to provide mechanism by which a switch may be thrown on and off by independent means.

Another object of my invention is to provide switch mechanism suitable for use in connection with an automatic zeolite water softener, and capable of being thrown on by means operable from the meter and capable of being thrown off by means of the flow controlling mechanism. It is particularly important for such use that the switch mechanism be inexpensive to make, and simple and sturdy so that it shall require the minimum amount of attention after being put in service.

In the particular embodiment of my invention selected for illustration a snap switch is shown as applied to an automatic zeolite water softening apparatus with independent cam means for throwing the switch on and off.

Figure 1 is a side elevation of a switch in position on the water softening apparatus with part of the cover broken away and sufficient of the water softening mechanism shown to show how the switch is operated.

Fig. 2 is a section on the line 2—2 of Fig. 1.

Referring now to the drawing, H is the housing of a portion of the water softening apparatus in which a cam shaft C is journaled at h. To the shaft C is fixed a cam c and another cam c¹ is loose on said shaft and is held in place by washer c² and nut c³. Two parallel lugs c⁴, c⁵ on the underside of the cam c¹ are so placed as to receive in the slot between them a pin m² fixed to an arm m¹ rotatably secured to the shaft m thus forming a flexible driving means for the cam c¹. The shaft m is in fact the shaft of a meter not shown whose housing M is also secured to the housing H. Also secured to the housing H is a switch-box A with a removable cover a. Through the back of the switch-box A extend the switch contact elements a¹ and a² secured to lead wires a³ and a⁴ respectively, said switch contacts a¹ and a² being insulated from the switch-box A by insulating member a⁵, which is preferably bored to receive the switch contacts a¹ and a², the body portions of which are then made cylindrical.

Within the chamber a⁶ of the switch-box

A is a lug a⁷ bored to receive a screw a⁸ which acts as a pivot for the oscillatable T-head switch blade composed of a body portion a⁹ of fiber and a head portion a¹⁰ of metal, the two being secured together by rivet a¹¹. To the outer end of this blade is secured the usual brass or phosphor-bronze forked blade a¹² secured to the portion a⁹ by rivet a¹³. Another lug a¹⁴ is bored and fitted with a pin a¹⁵ which acts as a stop to limit the oscillating movement of the blade. The corner a¹⁶ of the fiber member a⁹ of the blade may impinge upon the inner side of the case A as shown in Fig. 1 and act as a stop also.

The blade is thrown by means of either of the hooked members a¹⁷ and a¹⁸ pivoted by the pins a¹⁹ and a²⁰ respectively to pull-rods a²¹ and a²² respectively and upon which are mounted coiled springs s compressible in such a manner as to tend to throw the blade when the end of the pull-rod passes over the point of its cam.

A spring s¹ is adapted to press the hook of the member a¹⁷ into engaging position with the member a¹⁰ whenever the point of the cam c¹ has pressed inwardly the pull-rod a²¹ so that the heel a²³ of the hook member a¹⁷ no longer bears upon the inner surface of the chamber a⁶ of the case A, as shown in Fig. 2.

As soon as the outer end of the pull-rod a²¹ has passed over the point of the cam c¹ the spring s on said pull-rod causes the hook of the member a¹⁷, which is in engaging position with its end of member a¹⁰, to throw the blade of said switch into the position shown in Fig. 1. As soon as the switch blade has passed into position shown in Fig. 1 the heel a²³ of the hook member a¹⁷ contacts with the upright wall of the case and throws the hook out of engagement with the member a¹⁰. The action of the other hook member a¹⁸ through the pull-rod a²² by means of its cam is similar to that of the one just described.

Downward pressure of the springs s¹, s² on the hooks a¹⁷ and a¹⁸ cause those hooks to bear one at a time upon the metallic head a¹⁰ whenever they are in contacting position, with sufficient pressure to hold the T-head blade in positive position, whether contacting or non-contacting.

In both figures of the drawing the hook of the member a¹⁸ is shown depressed, that is,

in engagement with its end of the member a^{10} ready to throw the blade when the outer end of the pull-rod a^{22} has passed off the point of cam c . After the switch has been so thrown, the position of the parts will be as shown in dotted lines in Fig. 1.

If the position of the switch was that shown in dotted lines in Fig. 1 and for any reason it was desired to throw it by hand at 10 a time earlier than it would be thrown automatically by the operation of the water softening mechanism upon rotation of the cam c^1 , pressure to the left on the handle a^{24} would cause the hook on a^{17} to engage the member a^{10} 15 when the spring s on the pull-rod a^{21} will throw the switch into position shown in full lines in Fig. 1. A similar handle a^{25} may be provided for the pull-rod a^{22} .

I claim as my invention and desire to 20 secure by Letters Patent of the United States:—

1. In an electric switch mechanism, the combination of a positive contact element, a negative contact element, a T-headed switch 25 blade comprising a body portion of insulating material, a metallic head secured to said body portion and pivoted through said metallic head for oscillation and a metal switch contactor secured to said body portion toward its free end, said contactor adapted to 30 be brought into electrical connection with either of said elements, a pull-rod with a hook adapted to contact with one side of said metallic head to oscillate the blade on

its pivot so as to close the switch, a pull- 35 rod with a hook adapted to contact with the other side of said metallic head to oscillate the blade on its pivot so as to open the switch, and means for holding said blade in fixed relation to the contact element when oscillated into either of said positions. 40

2. In an electric switch mechanism, the combination of a positive contact element, a negative contact element, a T-headed switch blade comprising a body portion of insulating material, a metallic head secured to said body portion and pivoted through said metallic head for oscillation and a metal switch contactor secured to said body portion toward its free end, said contactor adapted to 50 be brought into electrical connection with either of said elements, a pull-rod with a hook adapted to contact with one side of said metallic head to oscillate the blade on its pivot so as to close the switch, a pull-rod 55 with a hook adapted to contact with the other side of said metallic head to oscillate the blade on its pivot so as to open the switch, means for holding said blade in fixed relation to the contact element when oscillated 60 into either of said positions and means for automatically disengaging said hooks from said metallic head when the blade has been oscillated to its new position in relation to said contact elements. 65

In testimony whereof I have hereunto set my hand.

EDWIN A. ROBERTSON.
